Primary Examiner — Eric Goodman*Assistant Examiner* — Daniel J Domino(74) *Attorney, Agent, or Firm* — Lerner, David, Littenberg, Krumholz & Mentlik, LLP**(57) CLAIM**

The ornamental design for a display screen or portion thereof with animated graphical user interface, as shown and described.

DESCRIPTION

FIG. 1 is a front view of a first image in a sequence for a display screen or portion thereof with animated graphical user interface according to our design; and,

FIG. 2 is a second image thereof.

The dash-dot broken line is provided for the purposes of illustrating the display screen or portion thereof whereas the even the broken lines illustrates portions of the animated graphical user interface. Neither the display screen nor the graphical user interface shown in broken lines form part of the claimed design.
